(57) **CLAIM**

The ornamental design for a cup with functional aperture, as shown and described.

DESCRIPTION

FIG. 1 is a front, top perspective view of a cup with functional aperture showing the new design;

FIG. 2 is a front elevation view thereof;

FIG. 3 is a left side elevation view thereof;

FIG. 4 is a rear elevation view thereof;

FIG. 5 is a right side elevation view thereof;

FIG. 6 is a top plan view thereof;

FIG. 7 is a bottom plan view thereof;

FIG. 8 is an in use front, top perspective view thereof; and,

FIG. 9 is a top side perspective view thereof.

The broken line showing of a can in FIG. 8 and a cooling insert in FIG. 9 are included for the purpose of illustration and form no part of the claimed design.
